UNITED STATES PATENT OFFICE.

ELWYN A. MALLORY, OF MILWAUKEE, WISCONSIN.

BAG-FASTENER.

1,318,893.

Specification of Letters Patent.

Patented Oct. 14, 1919.

Application filed December 14, 1916, Serial No. 136,980. Renewed February 24, 1919. Serial No. 278,937.

To all whom it may concern:

Be it known that I, ELWYN A. MALLORY, a citizen of the United States, residing at Milwaukee, in the county of Milwaukee and 5 State of Wisconsin, have invented certain new and useful Improvements in Bag-Fasteners, of which the following is a specification.

This invention relates to an improvement 10 in bag fasteners, and more particularly to a device of this character intended for use in fastening and holding in closed relation, the open top end of grain bags, cement sacks, and other bags or sacks of large size and 15 containing pulverulent or loose material which is likely to sift and to place strain upon the gathered in and closed end, thus making the use of a string or cord impractical.

20 I am aware that heretofore wire has been used in fastening the gathered in open end of cement and other bags of large size and of coarse or stiff material, however, in those instances of which I am aware the wire was 25 used by being wrapped around the end of the bag and twisted together at its ends, thus making the fastening somewhat difficult 30 to release and practically impossible for reuse, and it is a purpose of my invention 35 to provide a bag fastener preferably constructed of lengths of wire bent to the proper form and connected together in such manner that the gathered in open end of a bag or sack can be secured in the closed 40 relation and by a very simple manual manipulation the fastener can be released following which it may be reused upon same bags or upon other bags of like or dissimilar character.

45 A further object resides in so shaping the parts of the fastener by which the gathered or folded in end of the bag is held that the bag material is clamped within the portion and thus a fastener of stock size can be used 50 upon various types and characters of bags with equally efficient results, and to so construct the fastening members that they are readily applied around the gathered in end of the bag and then are brought toward each 55 other with a clamping movement and are secured in such relation that they positively grip and hold against the material of the bag.

Yet another object is to so construct the 55 securing means that it is held by the gath-

ered in end of the bag against casual or accidental movement to the position in which it is released from the fastening member.

With the above and other objects in view, 60 my invention consists in certain novel features of construction and combinations of parts which will be hereinafter set forth in connection with the drawings and then more particularly pointed out in the drawings.

In the drawings:— 65

Figure 1 is a view in elevation showing a fragmentary portion of the upper end of a bag with my invention applied thereon.

Fig. 2 is a view in perspective showing the fastener in the form which it takes 70 previous to application to a bag.

As has been stated, the fastener is intended to be applied to the gathered in top end of a bag or sack after the filling of the same, and the bag embracing members 1 and 75 2, which are each preferably made up of a single length of wire, are bent to provide the loops 3 and 4, after which the two ends of the wire are twisted together to form the fulcrum portions 5 and 6 from which 80 the ends spread in branched relation to take substantially a Y-shape. At the ends of the wires closing the member 2, the eyes or loops 7 and 8 are formed, and a loop 9 formed at the extremity of one of the branched ends 85 of the wire closing the member 1 is engaged through the loop or eye 7 of the member 2 thus hinging the two members together. The remaining end of the wire from which 90 the member 1 is bent is formed into a hook 10, which preferably opens to have the bill thereof disposed downwardly when the fastener is secured in place. A locking bar 11 has an eye or loop 12 at one end thereof 95 mounted through the loop 4 of the member 2, and the remaining end of this locking bar 11 is formed into a hook 13.

In the use of the device, the top of the bag is gathered in and has its open end drawn in tightly slightly below the extreme 100 edge. The bag embracing members 1 and 2 are then opened by releasing the hook 10 from the eye 8 and taking these released ends of the wire apart around the connection through the eyes 7 and 9 at a hinged 105 joint. The gathered in portion of the bag top is then fitted within the substantially Y-shaped branched ends of the members 1 and 2 and the fulcrums 5 and 6 are thus 110 swung to extend in alinement in which rela-

tion of the parts the hook 10 may be inserted through the eye 8. This binding action as obtained by the placing of the hook 10 within the eye 8, will hold the bag top 5 with a reasonable degree of security, due to the naturally elastic or resilient qualities of the material of the bag or sack which will spring out at its end over the branch arms of the members 1 and 2 and will hold 10 these bag embracing members against displacement, however, it is advisable that the members 1 and 2 be positively clamped against the bag to insure that a more secure fastening grip is obtained upon the closed 15 end thereof. The fulcrums 5 and 6 are moved upwardly and are consequently swung inwardly, and the locking bar 11 is then swung down against the top of the bag and is inserted through the loop 3 of the 20 member 1 sufficiently that the bill 14 of the hook 13 clears the loop 3, following which the pressure of the bag against this locking bar tending to move the same upwardly in a swinging path around its hinged connection in the loop 4, while the members 1 25 and 2 will have pressure exerted thereagainst to swing the same outwardly and consequently the locking bar will be moved upwardly and the outward movement of the 30 embracing members 1 and 2 will cause the loop 3 to be engaged beneath the bill of the hook 13. When it is desired to again release the fastening, the fulcrums 5 and 6 will be grasped and forced toward each other and 35 the locking bar 11 will be then forced downwardly until the bill 14 of the hook 13 clears the loop 3 when the fulcrums may be released and the hook 13 will be withdrawn from the loop 3. The hook 10 can then be 40 removed from the loop or eye 8 and the bag embracing members 1 and 2 opened and removed from the closed end of the bag.

From the foregoing it will be seen that I have provided a bag fastener which can be 45 used in holding closed and securing grain bags, cement sacks, and bags and sacks as used in a number of other connections, and which device is so constructed that it is very readily attached and removed and may 50 be reapplied or used in conjunction with another bag, and while I have herein shown and described only specific construction and specific arrangements of the parts, it will of course be understood that changes and 55 variations might be resorted to in the form and arrangement of the several parts without departing from the spirit and scope of my invention, in view of which fact I do not wish to be limited to the exact disclosure 60 but only to such points as may be set forth in the claims.

I claim:

1. A bag fastener including means to embrace and to be connected together to hold 65 the open end of a bag when the same is

gathered in to close the bag, and means to secure the embracing means against removal.

2. A bag fastener including means to be removably fitted and connected to embrace 70 and hold the open end of a bag when the same is gathered in to close the bag, and means to be releasably connected with said embracing means to secure the same against casual or accidental removal. 75

3. A bag fastener including a pair of bag embracing members shaped to be fitted to and having portions thereof connected around the end of a bag when the same is gathered in to close the bag, and means to 80 be connected between said members to secure the same against removal.

4. A bag fastener including a pair of bag embracing members shaped to have branched portions thereof received and 85 fastened around the end of a bag when the same is gathered in to close the bag, and a locking bar carried by one of said members to have connection with the remaining member to secure the same against being released. 90

5. A bag fastener including a bag embracing member shaped from a single length of wire bent to form a loop and with the ends thereof disposed in branched relation and 95 provided at their extremities with loops, a second bag embracing member shaped to have a loop in the body portion and with the ends branched and provided with a loop and a hook formation, the loop of the second 100 mentioned member being connected through one of the loops of the first mentioned member in such relation that the branched portions of the bag embracing members may be fitted around the upper end of a bag when 105 the same is gathered in to close the bag and the hook may be inserted through the remaining loop of the first mentioned member to secure the parts, and means carried by the body loop of one of said members to 110 be engaged through the body loop of the remaining member and to secure the members against removal.

6. A bag fastener including a bag embracing member shaped from a single length 115 of wire bent to provide a loop substantially at the center of the body portion with the adjacent extent of the wire twisted to form a fulcrum arm and the ends branched from the fulcrum arm and shaped to provide 120 eyes, a second bag embracing member also formed from a single length of wire bent to provide a loop at substantially the center of the body portion and having the adjacent portions twisted to form a fulcrum arm 125 with the ends of the length of wire branched and formed into an eye and a hook, the eye of the second mentioned member being fitted through one of the eyes of the first mentioned member to hinge the members to 130

gether in such relation that the gathered in
end of the bag may be fitted in the branched
portions of the members and the hook of the
second mentioned member may be inserted
5 through the remaining eye of said first
member to hold the parts upon a bag, and a
locking bar provided with a loop at one
of its ends mounted through the loop of one
10 of said bag embracing members and the
locking bar provided with a hook at the re-
maining end to be fitted through the loop of

the remaining bag embracing member and
to thus secure the two members in a clamped
position against the bag and hold the same
against casual or accidental displacement. 15

In testimony whereof I affix my signature
in presence of two witnesses.
